UNITED STATES PATENT OFFICE

LEON A. DANCO, OF FAIRFIELD, CONNECTICUT, ASSIGNOR TO MCKESSON & ROBBINS, INCORPORATED, OF BRIDGEPORT, CONNECTICUT, A CORPORATION OF CONNECTICUT

DESIGN FOR A TAG FOR CONTAINERS

Application filed October 12, 1929. Serial No. 33,019. Term of patent 14 years.

To all whom it may concern:

Be it known that I, LEON A. DANCO, a citizen of the United States, residing at Fairfield, county of Fairfield, State of Connecticut, have invented a new and original Design for a Tag for Containers, of which the following is a specification, reference being had to the accompanying drawing, forming part thereof.

The figure is a plan view of the tag for containers illustrating my new design.

I claim:

The ornamental design for a tag for containers substantially as shown.

LEON A. DANCO.
